ROTARY SWITCH ACTUATOR

Robert A. Pusch, Le Roy, Ill., assignor to General Electric Company, a corporation of New York
Filed Dec. 29, 1961, Ser. No. 163,274
10 Claims. (Cl. 74—504)

This invention relates to switch actuators and has particular relation to switch actuators of the rotary type.

Switch actuators of the rotary type have heretofore been constructed to include a rotatable shaft having thereon means, such as a cam, for actuating a switch operator, and a manually actuatable element attached to the shaft for effecting rotation thereof. Rotation of the shaft is transmitted through the switch operator to operate one or more switch contacts. Such switch actuators have heretofore included means for controlling the rotary position of the shaft. For example, rotary switch actuators have heretofore included means for providing a spring-return action when the shaft is rotated in either direction from a neutral position and released. Also, means have previously been provided to maintain the shaft in either of two positions spaced from a neutral position when the shaft is rotated to such positions and released.

In many installations it is desirable to provide a rotary switch actuator including a manually rotatable element or turn button which is rotatable from a neutral position in opposite directions to a pair of operating positions, and to provide means for maintaining the turn button in one of the operating positions when released, and to provide a spring-return mechanism for returning the turn button to the neutral position when the button is rotated to the other of its operating positions and released. Such an actuator may be defined as a three-position, spring return, maintained rotary actuator.

It is therefore a primary object of the present invention to provide a novel and improved rotary switch actuator of the three position, spring return, maintained type which is of inexpensive and compact construction and which incorporates a minimum number of parts.

It is another object of the invention to provide a novel and improved rotary switch actuator including separate means for returning a rotatable shaft to a neutral position from a first operating position when the shaft is released and for maintaining the shaft in a second operating position when rotated from a neutral position with a minimum of undesirable interference between the separate means.

It is a further object of the invention to provide a rotary switch actuator including separate means for returning a rotatable shaft to a neutral position from a first operating position when the shaft is released and for maintaining the shaft in a second operating position when rotated from a neutral position, such separate means being designed to take up a minimum amount of space in dimensions extending both radially and axially of the shaft.

In carrying out the invention in one preferred form there is provided a rotary switch actuator including a shaft supported within a hollow base for rotation and carrying a cam for actuating a switch operating element. The shaft is connected to a rotatably mounted, manually actuatable turn button for rotation therewith from a neutral rest position in opposite directions to a pair of spaced operating positions. In order to provide a spring return function for returning the shaft from one of the operating positions to a neutral position when released, a tension spring is provided which is wrapped around the shaft and having ends engaged respectively with a pair of axially spaced plates surrounding the shaft which

2

have relative movement for one direction of rotation of the shaft to elongate the spring and provide the return function, and which have no relative movement for the other direction of rotation of the shaft in which the maintained function is desired. The maintained function is provided by means of a cam and leaf spring arrangement which are movable relative to each other in response to rotation of the shaft in the direction for which a maintained function is desired. The cam is preferably carried by the switch operating cam on the shaft and the leaf spring is supported by the base.

Other objects and advantages of the invention will become apparent from the following description taken in conjunction with the accompanying drawings in which,

FIG. 1 is a view in elevation with parts shown in section of a switch including a rotary switch actuator constructed in accordance with the teachings of the present invention;

FIG. 2 is a view in section taken along the line 2—2 of FIG. 1;

FIG. 3 is a view in section taken along the line 3—3 of FIG. 1;

FIG. 4 is an exploded view with parts shown in perspective of elements of the actuator;

FIG. 5 is a view in section taken along the line 5—5 of FIG. 3;

FIG. 6 is a view section showing an actuator of modified form with a different type of maintaining mechanism;

FIG. 7 is a view in bottom plan of the actuator of FIG. 6 with a part removed; and

FIG. 8 is a view in perspective of a part of the maintaining mechanism of the actuator of FIGS. 6 and 7.

Referring now to the drawing there is illustrated in FIG. 1 a switch structure including a rotary switch actuator 10 having secured thereto a contact block 11 which may be of the construction set forth in copending application S.N. 77,576, filed December 22, 1960 by R. A. Pusch et al. and assigned to the assignee of the present invention, now Pat. No. 3,118,026, issued July 28, 1964. The actuator 10 includes a hollow base 12 having a central cavity 13 and having an upper end as viewed in FIG. 1 which is externally threaded at 14 to threadably engage internal threads on a ring 15. The base 12 includes an external annular flange 16 adapted to cooperate with the ring 15 to mount the actuator 10 and contact block 11 to a panel 17 which engages the lower surface of a spacer 17' between the panel 17 and the ring 15 and which also engages the upper one of a plurality of spacers 18 resting on the upper surface of the flange 16.

The actuator 10 includes a turn button 20 which is rotatably supported by the ring 15 and which includes an integral projection 21 extending through an upper opening of the ring 15 and containing a square socket 22 adapted to receive a square extension 23 formed on the upper end of a shaft 24. The button 20 is secured to the ring 15 by a C-shaped clamp 25 fit in a groove of the projection 21 and engaging the inner surface of the end wall of ring 15. The shaft 24 is mounted for rotation within the base by an internal flange 26 at the upper end of the base and by a centrally apertured washer 27 secured to the inner wall of the base adjacent the lower end of the base. A sealing gasket 28 is positioned on the flange 26 in the space between the upper end of the shaft 24 and the inner wall of the base.

In order to effect operation of switches in the block 11 there is provided a cam 30 secured to the lower end of the shaft 24 by means of a screw 31. The cam 30 rotates in response to rotation of the shaft 24 and includes a plurality of cam surfaces upon which rests a

vertically movable actuator 32 as viewed in FIG. 1 adapted to reciprocate to move contacts carried thereby into and out of engagement with fixed contacts within the block 11 in response to rotation of the cam 30. Details of the contact arrangement within the block 11 and further details of the configuration of the cam 30 may be found in the aforementioned Pusch et al. application.

According to the present invention means are provided to effect a spring-return function when the shaft 24 is rotated from a neutral position to an operating position and is released at such operating position. The invention also contemplates the provision of a maintaining operation wherein the shaft 24 is maintained in another operating position when rotated thereto from the neutral position and released. It is desirable that the spring-return mechanism be operative only when the shaft is rotated in the direction for which the spring-return function is desired, and be inoperative or ineffective when the shaft is rotated in the opposite direction for which the maintained function is desired. The means for providing the spring-return function will now be described with particular reference to FIGS. 1, 2 and 4.

As shown in FIGS. 1, 2 and 4, a tension spring 35 of coil configuration is wrapped about the shaft 24 and has its ends engaged respectively by tabs or hooks 36 and 37 formed on a pair of axially spaced centrally apertured rings or disks 38 and 39. The disks 38 and 39 include respectively confronting collars 40 and 41 which fit within a tube 42 surrounding the shaft 24 and the assembly including the spring, disks and the tube is positioned in the space between the washer 27 and the flange 26 of the base. The disk 39 includes a radially extending projection 45 adapted to engage one side of a vertically extending ridge 46 formed on the inner wall of the base. The projection 45 is also arranged to be contacted at its side by an upwardly extending tab 47 on the cam 30 in response to rotation of the button 20 and the cam 30 in the clockwise direction indicated by the arrows CW as viewed in FIG. 4. The shaft 24 includes an annular shoulder 48 beneath and overlapping the flange 26 and having a downwardly projecting tab 49 adapted to engage the lateral surface of a projection 50 of the disk 38 in response to rotation of the button 20 and the cam 30 in a counterclockwise direction as indicated by the arrows CCW in FIG. 4.

In operation it will be initially assumed that the button 20 is at its neutral rest position shown in FIG. 1. In this position the parts are arranged such that the tab 49 on the shaft 24 engages the projection 50 of the disk 38. When the button 20 is rotated in the counterclockwise direction, the tab 49 effects movement of the disk 38 in a corresponding direction by engagement of the projection 50, and the spring 35 is extended due to the fact that the projection 45 of the disk 39 engages the ridge 46 and is stopped against rotation. Therefore a relative movement between the disks 38 and 39 occurs tending to extend the spring 35 for counterclockwise rotation of the button 20. When the button 20 is released after movement thereof to an operating position, the spring 35 contracts and draws with it the disk 38 and the shaft 24 through the agency of the tab 49 back to the normal neutral position.

For rotation of the button 20 in the clockwise direction the tab 47 on cam 30 engages the projection 45 of disk 39 to rotate disk 39 in the clockwise direction. The projection 50 of disk 38, however, is not long enough to contact the ridge 46 and therefore disk 38 rotates with disk 39. For this condition then there is no relative movement between the disks 38 and 39 and therefore, there is no elongation of the spring 35 and no spring return function for clockwise rotation of the button 20. Another arrangement for preventing relative rotation between disks 38 and 39 for clockwise rotation of button 20 would consist of removing tab 47 from cam 30. Rotation of button 20 in the clockwise and counterclockwise

directions is limited by engagement of the tab 47 with radially extending surfaces 27a and 27b of the washer 27.

The maintaining function is effective when the button 20 is rotated in the clockwise direction. This function is effected by means of a detent mechanism including engageable parts on the base 12 and on the cam 30 which latching engage in response to rotation of the cam 30 relative to the base 12 in the clockwise direction to the second operating position. In one embodiment of the invention shown in FIGS. 3 and 5 the detent mechanism includes a generally flat leaf spring 60 secured to the undersurface of the washer 27 as by welding indicated at the point 61. The spring 60 includes a downwardly-extending projection 62 adapted to engageably cooperate with an upwardly-projecting triangular cross-section extension 63 on the upper surface of the switch operating cam 30. The free end 64 of the spring 60 is located beneath a slot 65 formed in the washer 27 and which serves to permit upward movement of the spring 60 in response to engagement of the projection 62 thereof with the extension 63.

In operation, when the button 20 is rotated in a clockwise direction as viewed in FIGS. 3 and 4, the extension 63 on the cam 30 is rotated in a corresponding direction relative to the washer 27 and the spring 60 secured thereto. As the button 20 approaches the second operating position, the gradually sloped leading surface of the extension 63 engages the projection 62 of the spring 60 to elevate the spring, and continued rotation of the button 20 results in passage of the apex of the extension 63 by the lowermost part of the projection 62 and downward movement of the spring into engagement with the severely sloped trailing surface of the extension 63. With this arrangement the button 20 and the cam 30 are held in such position when the button 20 is released, and a certain positive force acting on the button 20 in the counterclockwise direction is necessary in order to move the extension 63 past the projection 62 and effect return of the button and the cam 30 to the neutral position. As previously described herein, during rotation of the button 20 in the clockwise direction there is no elongation of the spring 35. Also, there is no appreciable friction between the projection 62 of the spring 60 and the upper surface of the cam 30.

Other arrangements of the detent mechanism are possible. For example, the spring 60 may be formed with an extended free end and be secured at both of its ends to the washer 27. This arrangement gives an increase in the detenting force over that wherein the spring is secured only at its right hand end as viewed in FIG. 5.

FIGS. 6, 7, and 8 illustrate a different arrangement of the detent mechanism for providing the maintained function. Similar parts in the devices of FIGS. 6 and 1 are represented by the same reference numerals. In the arrangement of FIGS. 6-8 a curved split spring 70 replaces the spring 60 and is positioned to surround the periphery of the cam 30. The spring 70 includes a pair of spaced ends 71 and a pair of diametrically-opposed slots 72 which engage respectively a projection 73 formed on the washer 27 and a ridge 74 on the inner wall of the base. Spring 70 includes a projection 75 adjacent one of its ends and extending radially inwardly thereof to engage an outwardly extending extension 76 formed on the periphery of the cam 30. The operation of the arrangement shown at FIGS. 6 and 7 is similar to that shown in FIGS. 3 and 5 and need not be described in detail.

It is thus seen that a rotary switch actuator is provided including unique means for effecting a spring return function for one direction of rotation of the button 20 from a neutral position, and for effecting a maintained function for rotation of the button 20 in the opposite direction. The arrangement is such that the mechanisms for providing the two functions do not interfere with each other and the spring return function is rendered ineffec-

tive for rotation of the button 20 in the maintained direction. Also, the two mechanisms take up a very small space in the actuator, include a minimum number of parts, and are inexpensive to manufacture, all of which results in a very efficient, inexpensive and compact rotary switch actuator.

Although the invention has been described with reference to certain specific embodiments thereof, numerous modifications are possible, and it is desired to cover all modifications falling within the spirit and scope of the invention.

What I claim as new and desire to secure by Letters Patent of the United States is:

1. In a rotary switch actuator, a hollow base, a shaft having a cam portion at one end for actuating a switch, means on said base including an apertured plate spaced axially of the cam portion for mounting the shaft for rotation from a neutral position in opposite directions to first and second operating positions, restoring means on one side of said plate and effective in response to rotation of said shaft to said first position only and release of said shaft at said first position to return the shaft to said neutral position, said restoring means including a spring, and means for stressing said spring in response to rotation of said shaft to said first position and for preventing stressing of said spring in response to rotation of said shaft to said second position, and detent means on the other side of said plate including parts on said plate and on said cam portion in the space therebetween engageable to latch the shaft in said second position in response to rotation thereof to said second position.

2. An actuator as defined in claim 1 wherein said detent means includes a leaf spring on said plate having a projection, and an extension projecting from said cam portion to latchingly engage said projection when the shaft is rotated to said second position.

3. In a rotary switch actuator, support means, a shaft having a cam portion at one end for actuating a switch, mounting means on said support means mounting the shaft for rotation from a neutral position in opposite directions to first and second operating positions, a coil spring wrapped around the shaft, a pair of rings secured to opposite ends of said spring, means for effecting relative rotation between said rings to stress said spring in response to rotation of the shaft to said first position, and for effecting rotation of the rings as a unit to prevent stressing of said spring in response to rotation of the shaft to said second position, and detent means including a leaf spring on said mounting means and an extension on said cam portion engageable when said shaft is rotated to said second position to latch the shaft in said second position.

4. An actuator as defined in claim 3 wherein said leaf spring is generally flat and includes a projection extending axially of said shaft, said extension projecting from said cam portion toward said projection.

5. An actuator as defined in claim 3 wherein said mounting means includes an apertured plate, said coil spring and said detent means being on opposite sides of said plate.

6. In a rotary switch actuator, support means, actuating means mounted by said support means for rotation from a neutral position in opposite directions to first and second operating positions, restoring means operatively engageable with said actuating means and effective in response to rotation of the actuating means to said first position only and release of said actuating means at said first position to return the actuating means to the neutral position, and detent means including parts on said support means and on said actuating means engageable to latch said actuating means at said second position in response to rotation thereof to said second position, said restoring means including a coil spring wrapped about said actuating means, and means connected to the ends of said spring

relatively rotatable to extend the spring in response to rotation of the actuating means to said first position, and rotatable as a unit to prevent extension of the spring in response to rotation of the actuating means to said second position.

7. In a rotary switch actuator, support means, actuating means mounted by said support means for rotation from a neutral position in opposite directions to first and second operating positions, restoring means operatively engageable with said actuating means and effective in response to rotation of the actuating means to said first position only and release of said actuating means at said first position to return the actuating means to the neutral position, and detent means including parts on said support means and on said actuating means engageable to latch said actuating means only at said second position in response to rotation thereof to said second position, said detent means including a leaf spring on said support means, and an extension on said actuating means latchingly engageable with said leaf spring in response to rotation of said actuating means to said second position, said restoring means including a coil spring wrapped about said actuating means, and means connected to the ends of said spring relatively rotatable to extend the spring in response to rotation of the actuating means to said first position, and rotatable as a unit to prevent extension of the spring in response to rotation of the actuating means to said second position.

8. In a rotary switch actuator, a hollow base, a shaft having a cam portion at one end for actuating a switch, means on said base including an apertured plate spaced axially of the cam portion for mounting the shaft for rotation from a neutral position in opposite directions to first and second operating positions, restoring means surrounding said shaft and effective in response to rotation of said shaft to said first position only and release of said shaft at said first position to return the shaft to said neutral position, and detent means including parts on said plate and on said cam portion in the space therebetween engageable to latch the shaft in said second position in response to rotation thereof to said second position, said restoring means including a coil spring wrapped around said shaft, a pair of rings secured to opposite ends of said spring, and means for effecting relative rotation between said rings to stress said spring in response to rotation of the shaft to said first position, and for effecting rotation of the rings as a unit to prevent stressing of said spring in response to rotation of the shaft to said second position.

9. In a rotary switch actuator, support means, actuating means mounted by said support means for rotation from a neutral position in opposite directions to first and second operating positions, a coil spring wrapped about said actuating means, a pair of rotatable rings surrounding the actuating means and each having a hook secured to a separate end of said spring, said hooks being spaced angularly about the axis of rotation of the actuating means relative to each other when the actuating means is in the neutral position, each ring having also a radially extending projection spaced angularly about the axis of the actuating means with respect to its associated hook, said projections also being spaced angularly about the actuating means with respect to each other when the actuating means is in the neutral position, the projection of one of said rings having a greater radial extent than the projection of the other of said rings, said support means having a ridge extending radially into the path of rotation of the projection of said one of said rings and extending short of the path of rotation of the projection of said other of said rings, said actuating means having an axially extending tab adapted for engagement with the projection of said other of said rings, said other of said rings being rotated by engagement of its projection by said tab in response to rotation of the actuating means

toward said first position away from said neutral position to stretch said spring while said one ring is held against rotation by engagement of its projection with said ridge, said tab being moved away from the projection of said other of said rings in response to rotation of the actuating means toward said second position from said neutral position to prevent relative rotation of said rings, and detent means including parts on said support means and on said actuating means engageable to latch said actuating means at said second position in response to rotation thereof to said second position.

10. In a rotary switch actuator, a hollow base, a shaft having a cam portion at one end for actuating a switch, means on said base including an apertured plate spaced axially of the cam portion for mounting the shaft for rotation from a neutral position in opposite directions to first and second operating positions, a coil spring on one side of said plate wrapped around the shaft, a pair of rotatable rings on said one side of said plate surrounding the shaft and each having a hook secured to a separate end of said spring, said hooks being spaced angularly about the axis of the shaft relative to each other when the shaft is in a neutral position, each ring having also a radially extending projection spaced angularly about the shaft axis with respect to its associated hook, said projections also being spaced angularly about the shaft axis with respect to each other when the shaft is in said neutral position, the projection of one of said rings having a greater radial extent than the projection of the other of said rings, said base having a ridge extending radially into the path of rotation of the projection of said one of said rings and extending short of the path of rotation of the projection of said other of said rings, said shaft having an axially extending tab adapted for engagement with the projection of said other of said rings, said other of said rings being rotated by engagement of its projection

5 with said tab in response to rotation of the shaft toward said first position away from said neutral position to stretch said spring while said one ring is held against rotation by engagement of its projection with said ridge, said tab being moved away from the projection of said other of said rings in response to rotation of the shaft toward said second position from said neutral position to prevent relative rotation of said rings, and detent means including cooperating parts engageable to latch the shaft 10 in said second position in response to rotation thereof to said second position, one of said cooperating parts being fixed and the other cooperating part being rotatable with the shaft relative to the one cooperating part, both of said cooperating parts being positioned in the space between said plate and the cam portion on the other side of said plate.
